UNITED STATES PATENT OFFICE.

HEINRICH HOEGLAUER, OF MUNICH, GERMANY.

DEVICE FOR GENERATING WAVES IN BATHS.

No. 826,427.

Specification of Letters Patent.

Patented July 17, 1906.

Application filed March 22, 1906. Serial No. 307,478.

To all whom it may concern:

Be it known that I, HEINRICH HOEGLAUER, a citizen of Germany, residing at Munich, Bavaria, Germany, have invented certain new and useful Improvements in Devices for Generating Waves in Baths; and I do hereby declare the following to be a full, clear, and exact description of the invention, such as will enable others skilled in the art to which it applies to make and use the same.

The present invention consists of a device for generating waves in baths; and the object is to provide a simple and effective device which may readily be applied to existing baths and by means of which the waves may be generated either by hand by the bather or by means of a small motor or the like.

In order to render the present specification easily intelligible, reference is had to the accompanying drawings, in which similar letters of reference denote similar parts throughout the several views.

Figure 1 is a vertical section through a built-in bath; Fig. 2, a similar section 25 through an ordinary bath, showing the wave-generating device; Fig. 3, a similar section showing a modification of the device; Fig. 4, a part-vertical longitudinal section showing a further modification; Fig. 5, a cross-section 30 showing the form of wave-generating flap or body, and Fig. 6 a part-vertical section showing yet another modification of the flap or wing.

In Fig. 1 the wave-generating flap or wing 35 *a*, which may be full or, as shown in Fig. 5, recessed at *b*, is pivoted at its lower end at *a'* to the bottom of the bath and may be swung to and fro by means of a connecting rod or line or in any other suitable manner to produce 40 the waves.

In Fig. 2 a flap or wing *a*, having a recess *b*, is pivoted at the upper part of the bath at one end of the same and provided with a weight *e*, which tends to hold the said flap in 45 one of its end positions. A rod *c* serves to

rock the flap out of its end position, to which it will be returned by the said weight *e*.

In Fig. 3 the flap is pivoted to the bottom of the bath at *a'* and swung by means of a rod *c*.

In Fig. 4 the flap is horizontally guided on 50 guide-bars *ff* and returned to its initial position by means of a spring *d* and may be pulled forward by means of a rod or cord *c'*.

Fig. 6 shows the flap *a* with recess *b* mounted on swinging bars *e' e'*, pivoted at *e e* to the 55 walls of the bath. This flap may also be operated by means of a rod, as indicated.

In all cases instead of a rod and springs, the flaps may be operated by means of a 60 small motor, as will be readily understood. When the flap is recessed, it leaves room for the feet of the bather.

The arrangement of the flap and method of operating the same might be varied in many ways, as will be readily understood, without 65 departing from the spirit of the invention.

I claim as my invention—

1. The combination with a bath-tub, of a flap arranged therein, said flap cut away to form a recess in its lower portion, and means 70 for moving said flap in a general horizontal rectilinear direction against the body of water confined in the tub.

2. A device for generating waves in connection with baths, consisting of a flap having pivoted arms thereon, said arms having 75 their ends pivoted to the walls of the bath and means for rocking the said flap to and fro in the bath.

3. A device for generating waves in connection with baths consisting of a flap having a recess, said flap being pivotally mounted within the bath and means for rocking it to and fro within the bath.

In testimony whereof I hereunto affix my 85 signature in the presence of two witnesses.

HEINRICH HOEGLAUER.
